SPENCER G. NEAL, OF LOS ANGELES, CALIFORNIA, ASSIGNOR TO CALIFORNIA VALVE AND AIR BRAKE COMPANY, OF LOS ANGELES, CALIFORNIA, A CORPORATION OF CALIFORNIA.

QUICK-ACTION RELEASE MECHANISM FOR AIR-BRAKES.

1,128,622.

Specification of Letters Patent. Patented Feb. 16, 1915.

Application filed November 2, 1914. Serial No. 869,773.

To all whom it may concern:

Be it known that I, SPENCER G. NEAL, a citizen of the United States, and resident of Los Angeles, county of Los Angeles, and 5 State of California, have invented certain new and useful Improvements in Quick-Action Release Mechanism for Air-Brakes, of which the following is a specification.

This invention relates to certain improvements in the braking apparatus shown in 10 my Letters Patent No. 1,082,758, dated December 30, 1913. By means of the apparatus shown and described in that patent the train line, or train pipe is the source of air 15 supply during service braking, and the train pipe, or train line, capacity is increased by providing a reservoir for each braking unit, from which reservoir the train pipe is supplied locally during service 20 applications of the brakes. In the operation of braking apparatus such as that shown in my said patent, and as shown in my Patent No. 1,078,303, dated November 11, 1913, it has been found that it requires considerable 25 time to release the brakes on a long train by increasing the train pipe pressure from the main reservoir of the locomotive. It is manifest that should a train be started before the brakes on the rear cars are released 30 the couplings are likely to be broken and the train parted. In very long trains the time required for releasing the brakes on the rear cars is considerable, and varies to such an extent that it is difficult for the 35 engineer to accurately determine when it is safe to start his train. Frequently a train will be prematurely started with the result that the couplings and braking apparatus on the rear cars are damaged, if not broken 40 and the train parted.

It is one of the main objects of this invention to provide means for rapidly increasing train pipe pressure locally under each car by placing the auxiliary reservoir in direct 45 communication with the train pipe by a slight increase of train pipe pressure. By this means the train pipe pressure will be rapidly increased at each braking unit and the wave of increased pressure will move 50 with great rapidity throughout the train line. It is manifest that by producing a rapid increase in train line pressure at each braking unit by discharging the air from each auxiliary reservoir into the train line,

the increase in train line pressure sufficient 55 for the releasing action will be almost instantaneous throughout the train line, and this practically without regard to the length of the train line. It is also manifest that in a braking apparatus operating as described 60 the air taken from the main reservoir on the locomotive need only be sufficient to operate the releasing device or valve on the first car of the train, or on the first car equipped with the quick-release apparatus, 65 so that the main reservoir will not be depleted to any material extent to secure the quick-releasing action.

Another object of the invention is to provide a valve device adapted to be placed between the train line augmenting reservoir of my Patent No. 1,082,758 and the train line, said valve device containing means for placing the auxiliary reservoir in communication with the train line upon an increase of 75 train pipe pressure after a service application of the brakes.

Another object of the invention is to provide means whereby the quick action release mechanism may be cut out or rendered 80 inoperative by closing communication between the auxiliary reservoir and said mechanism, the braking apparatus as a whole then operating precisely as shown and described in my said Patent No. 1,082,758, or 85 as it was originally intended and designed to operate, without the quick-action release mechanism.

Another object of the invention is to provide means for quickly discharging the 90 augmenting reservoir air into the train line and for slowly recharging the augmenting reservoir when the train line pressure is increased. The purpose of this is to permit the train line pressure to be raised rapidly 95 without the necessity of supplying sufficient air to quickly recharge the augmenting reservoir, the train line pressure being thereby raised rapidly in advance of the increase in pressure in the augmenting reservoir.

While I have indicated herein that this invention is adapted for use with my triple valve and braking apparatus shown in my Patent No. 1,082,758, it is to be understood that it may be used with other forms of 105 braking apparatus and triple valves, such, for instance, as disclosed in my Patent No. 1,078,303.

In the drawings, Figure 1 is a diagrammatic view of a braking unit showing the quick-action release mechanism combined with a braking unit; Fig. 2 a vertical central sectional view of the quick-action release valve device showing the parts in position for releasing the auxiliary reservoir air into the train line; Fig. 3 a similar view showing the valve mechanism in position to admit augmenting reservoir air into the train line, communication between the auxiliary reservoir and train line being closed; Fig. 4 a detail sectional view showing the valves for controlling communication between the augmenting reservoir and train line, with the parts in the position shown in Fig. 3; and Fig. 5 a detail view showing means for feeding air into the auxiliary reservoir through the quick-action release valve mechanism.

Referring to the various parts by numerals, 1 designates the train pipe or train line, 2 the brake cylinder, 3 the auxiliary reservoir, 4 the triple valve and 5 the train line augmenting reservoir. All these parts are shown and described in my Patent No. 1,082,758 hereinbefore referred to. These parts constitute what I term a braking unit and, of course, are repeated on each car of the train as described in my said patent.

Interposed in the train line and between the triple valve and the train line augmenting reservoir is a quick-action release valve mechanism, which as a whole is designated by the reference letter A. This valve mechanism consists of a main body part 6; a lower section or member 7 and an upper section or member 8, said sections being secured together by suitable bolts. The main casting or section is formed at its upper end with the large train line chamber 9. Across the upper end of this chamber is secured a main diaphragm 10, the marginal edges of said diaphragm being clamped between the upper section 8 and a flange on the upper end of the central section 6. The section 8 forms a train line augmenting chamber 11 above the diaphragm 10. In the main section 6 below the train line chamber 9 is formed an auxiliary reservoir chamber 12 coaxial with the train line chamber and of considerably smaller diameter. Closing the lower end of this chamber 12 is a diaphragm 13, said diaphragm, of course, being considerably smaller in diameter than the main diaphragm 10. The section 7 of the casing forms a train line chamber 14 below the diaphragm 13 equal in diameter to chamber 12, and said smaller chamber is in communication with the large train line chamber 9 through a passage 15. The train line chamber 14 is connected to the triple valve and to the train line through pipe 16, while the train line augmenting chamber 11 is connected to the augmenting reservoir through pipe

17. The auxiliary reservoir chamber 12 is connected to the auxiliary reservoir through pipe 18 and the passage 19 in the central section of the valve casing. In this passage 19 is a self-seating valve 20, said valve permitting air to flow from the auxiliary reservoir into the chamber 12 but seating and preventing air passing from the said chamber 12 into pipe 18.

Threaded through the wall 21 separating the auxiliary reservoir chamber from the train line chamber 9 is a bushing 22. This bushing is formed with a valve seat 23 on which seats a valve 24, said valve controlling communication between the auxiliary reservoir chamber and the train line chamber, the interior of said bushing being in direct open communication with the train line chamber through apertures 25. The valve 24 is formed on the lower end of a plunger 26, on the upper end of which is formed a valve 27, said valve being within the train line augmenting chamber 11 and above the diaphragm 10. The plunger 26 extends loosely through the central hub 28 of the main diaphragm clamping plates; and the valve 27 is adapted to engage a valve seat formed at the upper end of said central hub. The aperture through said hub is of such size that when the valve 27 is unseated there will be a free, unobstructed passage of considerable capacity connecting the train line chamber 9 with the augmenting reservoir chamber 11. Diaphragm 10 is free to move independently of the plunger 26, said diaphragm being what may be termed a "floating diaphragm" or abutment. Formed in the valve-carrying plunger 26 and connecting the train line chamber 9 with the augmenting reservoir chamber 11 is a restricted feed port 29, said port affording communication between said chambers when the valve 27 is seated and closed, so that train line air may feed slowly into the augmenting reservoir.

The lower clamping plate of the diaphragm 13 is formed with a central hub 30, said hub extending up into the auxiliary reservoir chamber 12. Connected to the upper end of this hub is a rigid stem 31 formed integral with the plunger 26, whereby said plunger and diaphragm reciprocate together. The lower clamping plate of said diaphragm 13 is formed with a depending guiding stem 32 which is suitably guided by the lower section 7 of the valve casing. Threaded through the upper wall of the section 8 of the valve casing is an adjustable stop 33 which limits the vertical movement of the plunger 26.

The operation of the apparatus may be briefly set forth as follows: When initially charging the apparatus, train pipe air flows through pipe 16 into chamber 14 and through passage 15 to chamber 9. Dia-

phragms 13 and 10 will be raised, thereby unseating valve 24 and opening communication between train line chamber 9 and auxiliary reservoir chamber 12 so that said chamber 12 will be charged to equalization with the train line and auxiliary reservoir. It will, of course, be understood that the auxiliary reservoir will be charged through the triple valve as described in my aforementioned Patent No. 1,082,758. When the diaphragm 10 has been raised and valve 27 seated, train line air will feed slowly through port 29 into the augmenting reservoir until said reservoir pressure is equalized with the train line and auxiliary reservoir. Upon a reduction of train pipe pressure to secure a service application of the brakes, pressure will be reduced in chambers 14 and 9, and diaphragm 10 will be depressed by the superior pressure in chamber 11 and diaphragm 13 will be depressed by the superior pressure in auxiliary reservoir chamber 12. The downward movement of the diaphragm 13 will seat valve 24 and close communication between train line chamber 9 and auxiliary reservoir chamber 12; and the downward movement of the diaphragm 10 will open free communication between the augmenting reservoir chamber 11 and train line chamber 9, thereby supplying the additional amount of air to the train line for effective application of the brakes, as described in my aforesaid Patent No. 1,082,758. Upon raising the train pipe pressure for a release of the brakes the increase of pressure in chamber 9 will immediately raise diaphragm 10 sufficiently to seat valve 27, and thereafter air from chamber 9 will feed slowly through port 29 into chamber 11 until there is an equalization of train line and augmenting reservoir pressures. When the diaphragm 10 has been raised sufficiently to seat valve 27 the upward pressure on said diaphragm tends to move upwardly the plunger 26 to unseat valve 24. As diaphragm 10 greatly exceeds in area the diaphragm 13, the pressure on said diaphragm 10 plus the train line pressure on the lower side of diaphragm 13 will cause the diaphragm 13 to move upwardly thereby unseating valve 24 and opening communication between the auxiliary reservoir chamber 12 and the train line chamber 9. As soon as valve 24 is unseated auxiliary reservoir air will unseat valve 20 and pass to chamber 12 and thence around valve 24 into train pipe chamber 9 and to the train pipe until there is an equalization of pressures in the train line and auxiliary reservoir. This rapid discharge of auxiliary reservoir air into the train line will quickly raise train line pressure locally under each car and there will be a quick equalization of pressures established between the train line and auxiliary reservoir and a slow equaliza-

tion in augmenting reservoir. In Fig. 2 the valves are shown in position permitting a discharge of auxiliary reservoir air into the train line. If a further service application be desired this may be secured by another reduction in train line pressure; and a further quick release may be obtained in the same manner as before described. It is manifest that by again raising train line pressure the valve device will be operated to discharge auxiliary reservoir air into the train line for another equalization of pressures and a quick release of the brakes. As set out in my aforesaid Patent No. 1,082,758, when train line pressure and auxiliary reservoir pressure are equalized the triple valve moves to full release position, and this action takes place without regard to the degree of equalization pressure. It will also be understood that after a release of the brakes a continued increase in train line pressure by means of main reservoir air will restore the various pressures to normal. In Fig. 3 valves are shown in position to permit augmenting reservoir air to pass into the train line.

If it be desired to dispense with the quick-action release valve mechanism, communication between the auxiliary reservoir and the auxiliary reservoir chamber 12 may be closed by means of a valve 34. When this valve is closed the quick-action release mechanism has no effect upon the operation of the remaining portion of the apparatus. The augmenting reservoir is slowly charged through the port 29 and will be rapidly discharged around valve 27 into the train line when the train line is reduced for brake applications. The valve 34 may be placed in any convenient position on the car, the pipe 18 being looped for the purpose. On long trains it may be found desirable to close the valve 34 on the cars at the head end of the train and to open it on the cars at the rear of the train. In this way all of the functions of the triple valves on the forward end of the train will be under the control of the engineer, while on those cars on which the valves 34 are open the quick-release action will be secured.

In order that the valve 27 shall normally tend to seat and close communication between the augmenting reservoir chamber 11 and train line chamber 9, I secure a flat spring 27^a across the upper end of the plunger 26, the ends of said spring being secured to the upper clamping plate of the diaphragm 10. This spring is kept under tension by means of set screws 27^b which adjustably connect the ends thereof to the upper plate of the diaphragm 10. This spring exerts an upward pulling pressure on the diaphragm 10 and a depressing pressure on the plunger 26. The purpose of the spring 27^a is to normally seat the valve 27

so that a slow raising of train pipe pressure will not be instantly registered on the opposite side of the diaphragm, which would be the case if the valve should remain open.

5 When the valve 24 is seated to close communication between the auxiliary reservoir 12 and the train line chamber 9 the lower end of the feed port 29 is moved below the upper end of the bushing 22 so that said 10 feed port is considerably restricted. The purpose of this is to insure the upward movement of the diaphragm 10 upon an increase of train pipe pressure and to prevent an equalization of pressure on both sides 15 of said diaphragm upon a slow and gradual increase of train line pressure. It is manifest that if this feed port were not restricted air would flow through said port in sufficient quantities to maintain an equalization 20 on both sides of the diaphragm 10 if there was a very slow increase in train pipe pressure.

If desired there may be a small feed port 35 formed either around valve 20 or through it, whereby air from the auxiliary reservoir chamber 12 may feed slowly into the auxiliary reservoir should the auxiliary reservoir pressure be less than the pressure in the said chamber 12. This feed port is shown 30 in Fig. 5 of the drawings.

What I claim is:

1. An air brake apparatus comprising a train line, a triple valve, an auxiliary reservoir, a brake cylinder, a train line augmenting reservoir, and a valve device interposed between the train line and the augmenting reservoir and operated by variations in train line pressure to place the auxiliary reservoir in communication with the train line.

40 2. An air brake apparatus comprising a train line, a brake cylinder, an auxiliary reservoir, a triple valve and a valve device actuated by train line pressure and auxiliary reservoir pressure and connected to the train line and to the auxiliary reservoir and operating upon an increase of train pipe pressure after a service application of the brakes to discharge the auxiliary reservoir air into the train line.

50 3. An air brake apparatus comprising a train line, a brake cylinder, an auxiliary reservoir, a triple valve operating to release the brakes upon an increase of train pipe pressure and a valve device actuated by train line pressure and auxiliary reservoir pressure and interposed between the train line and the auxiliary reservoir and operating upon an increase of train line pressure after a service application of the brakes to release the auxiliary reservoir pressure into the train line.

4. An air brake apparatus comprising a train line, a brake cylinder, an auxiliary reservoir, a triple valve operating upon a 65 reduction of train pipe pressure to admit

air to the brake cylinder and upon an increase of train pipe pressure to release the brakes, a valve device actuated by train line pressure and auxiliary reservoir pressure and interposed between the train line and the auxiliary reservoir and operating when train line pressure is increased after a service application to admit auxiliary reservoir air to the train line.

5. An air brake apparatus comprising a 75 train line, a brake cylinder, an auxiliary reservoir, a triple valve, a valve device actuated by train line pressure and auxiliary reservoir pressure and interposed between the train line and the auxiliary reservoir and adapted to operate to place the auxiliary reservoir in communication with the train line when the train line pressure is increased, after a service application of the 80 brakes.

6. An air brake apparatus comprising a 90 train line, a brake cylinder, an auxiliary reservoir, a triple valve, a train line augmenting reservoir and a valve device interposed between the said augmenting reservoir and the train line, said valve device operating upon a reduction of train line pressure to place the augmenting reservoir in communication with the train line, and upon an increase of train line pressure to place the auxiliary reservoir in communication with the train line.

7. An air brake apparatus comprising a 100 train line, brake cylinder, auxiliary reservoir, triple valve, a train line augmenting reservoir, a valve device interposed between the train line and the augmenting reservoir, a movable abutment therein subject to train line pressure and augmenting reservoir pressure, a second abutment in said device 105 subject to train line pressure and auxiliary reservoir pressure, a valve actuated by said abutments and operating upon an increase of train pipe pressure after a service application of the brakes to open communication between the auxiliary reservoir and the train line.

8. A quick-release mechanism for air brakes comprising a casing formed with a 115 train line chamber of large diameter and an auxiliary reservoir chamber below and smaller in diameter than the train line chamber, movable abutments secured across said chambers, a train line chamber below the abutment in the auxiliary reservoir chamber and connected with the larger train line chamber, a train line augmenting chamber above the movable abutment of the larger train line chamber and valves operated by said movable abutments to control communication between the auxiliary reservoir chamber and the train line chambers and between the train line chambers and the train line augmenting chamber.

9. A quick-release mechanism for air 120

brakes comprising a casing formed with a chamber of large capacity and with a chamber of considerably smaller capacity below and coaxial with the larger chamber, a movable abutment dividing the larger chamber into a train line chamber and a train line augmenting chamber, a movable abutment dividing the smaller chamber into an auxiliary reservoir chamber and a train line chamber, said latter chamber being in open communication with the larger train line chamber, and valves operated by said movable abutments to control communication between the auxiliary reservoir chamber and the train line chambers and between the train line chambers and the train line augmenting chamber.

10. A quick-release mechanism for air brakes comprising a casing formed with a chamber of large capacity and with a chamber of considerably smaller capacity below and coaxial with the larger chamber, a movable abutment dividing the larger chamber into a train line chamber and a train line augmenting chamber, a movable abutment dividing the smaller chamber into an auxiliary reservoir chamber and a train line chamber, said latter chamber being in open communication with the larger train line chamber, and valves operated by said movable abutments to control communication between the auxiliary reservoir chamber and the train line chambers and between the train line chambers and the train line augmenting chamber, said valves being connected to and moving with the abutment in the auxiliary reservoir chamber, the abutment subject to pressure in the train line augmenting chamber being movable independently of said valves.

11. An air brake apparatus comprising a train line, a triple valve, an auxiliary reservoir, a brake cylinder, a train line augmenting reservoir, a valve device interposed between the train line and the augmenting reservoir and operated by variations in train line pressure to place the auxiliary reservoir in communication with the train line, and means for closing communication between the auxiliary reservoir and the said valve device.

12. An air brake apparatus comprising a train line, a brake cylinder, an auxiliary reservoir, a triple valve operating upon a reduction of train pipe pressure to admit air to the brake cylinder, and upon an increase of train pipe pressure to release the brakes, a valve device interposed between the train line and the auxiliary reservoir and operating when train line pressure is increased after a service application to admit auxiliary reservoir air to the train line, and a valve to close communication between the auxiliary reservoir and said valve device.

13. A quick-release mechanism for air

brakes comprising a casing formed with a train line chamber of large diameter and an auxiliary reservoir chamber below and smaller in diameter than the train line chamber, movable abutments secured across said chambers, a train line chamber below the abutment in the auxiliary reservoir chamber and connected with the larger train line chamber, a train line augmenting chamber above the movable abutment of the larger train line chamber and valves operated by said movable abutments to control communication between the auxiliary reservoir chamber and the train line chambers and between the train line chambers and the train line augmenting chamber, and means in the train line augmenting chamber normally tending to close the valve controlling communication between the train line chamber and the train line augmenting chamber.

14. A quick-release mechanism for air brakes comprising a casing formed with a chamber of large capacity and with a chamber of considerably smaller capacity below and coaxial with the larger chamber, a movable abutment dividing the larger chamber into a train line chamber and a train line augmenting chamber, a movable abutment dividing the smaller chamber into an auxiliary reservoir chamber and a train line chamber, said latter chamber being in open communication with the larger train line chamber, and valves operated by said movable abutments to control communication between the auxiliary reservoir chamber and the train line chambers and between the train line chambers and the train line augmenting chamber, said valves being connected to and moving with the abutment in the auxiliary reservoir chamber, the abutment subject to pressure in the train line augmenting chamber being movable independently of said valves, and a spring in the train line augmenting chamber normally tending to move the abutment and close communication between the train line augmenting chamber and the train line chamber.

15. An air brake apparatus comprising a train line, a brake cylinder, an auxiliary reservoir, a triple valve and a valve device actuated by train line pressure and auxiliary reservoir pressure and connected to the train line and to the auxiliary reservoir and operating upon an increase of train pipe pressure after a service application of the brakes to release auxiliary reservoir air sufficient to equalize train pipe and auxiliary reservoir pressures.

16. An air brake apparatus comprising a train line, a triple valve, an auxiliary reservoir, a brake cylinder, a train line augmenting reservoir and a valve device interposed between the train line and the augmenting reservoir and operated by an increase in train line pressure to release air

from the auxiliary reservoir to equalize the pressure therein with train line pressure.

17. An air brake apparatus comprising a train line, a brake cylinder, an auxiliary reservoir, a triple valve and a valve device actuated by train line pressure and auxiliary reservoir pressure and operating upon an increase of train line pressure after a service application of the brakes to discharge auxiliary reservoir air into the train line.

18. An air brake apparatus comprising a train line, a brake cylinder, an auxiliary reservoir, a triple valve and a valve device operated by train line pressure and auxiliary reservoir pressure, said valve device upon a decrease of train line pressure for an application of the brakes being actuated by auxiliary reservoir pressure to close communication between the auxiliary reservoir and train line, and upon a subsequent increase of train line pressure to open communication between the auxiliary reservoir and the train line to discharge auxiliary reservoir air into the train line.

19. An air brake apparatus comprising a train line, a brake cylinder, an auxiliary reservoir, a triple valve, a valve device controlling communication between the auxiliary reservoir and the train line, differential diaphragms therefor, said device being operated by train line pressure on the larger diaphragm to open the valve and by auxiliary reservoir pressure on the smaller diaphragm to close the valve, whereby upon a reduction of train line pressure for an application of the brakes auxiliary reservoir pressure will close said valve and upon a subsequent increase in train line pressure auxiliary reservoir air will be discharged through said valve into the train line.

20. An air brake apparatus comprising a train line, a brake cylinder, an auxiliary reservoir, a triple valve, a valve device, a movable abutment therein subject to train line pressure, a second abutment in said device smaller than the first mentioned abutment and subject to train line pressure and auxiliary reservoir pressure, a valve actuated by said abutments and operating upon an increase of train line pressure after a service application of the brakes to open communication between the auxiliary reservoir and the train line.

21. An air brake apparatus comprising a train line, a triple valve, an auxiliary reservoir, a brake cylinder, a valve device interposed between the train line and the auxiliary reservoir and operated by variations in train line pressure to place the auxiliary reservoir in communication with the train line, and means for closing communication between the auxiliary reservoir and the said valve device.

22. An air brake apparatus comprising a

train line, a brake cylinder, an auxiliary reservoir, a triple valve and a valve device actuated by train line pressure and auxiliary reservoir pressure and connected to the train line and to the auxiliary reservoir and operating upon an increase of train line pressure after a service application of the 70 brakes to discharge the auxiliary reservoir air into the train line, and means for closing communication between the auxiliary 75 reservoir and the said valve device.

23. An air brake apparatus comprising a train line, a brake cylinder, an auxiliary reservoir, a triple valve adapted upon a reduction of train line pressure to place the 80 train line in communication with the brake cylinder for a service application of the brakes, and a valve device connected to the train line and to the auxiliary reservoir and operating upon an increase of train line 85 pressure after a service application of the brakes to discharge auxiliary reservoir air under the initially charged pressure into the train line.

24. An air brake apparatus comprising a 90 train line, a brake cylinder, an auxiliary reservoir, a triple valve adapted upon a reduction of train line pressure to place the train line in communication with the brake cylinder for a service application of the 95 brakes, and a valve device actuated by train line pressure and auxiliary reservoir pressure and connected to the train line and to the auxiliary reservoir and operating upon an increase of train line pressure after a 100 service application of the brakes to discharge the auxiliary reservoir air under the initially charged pressure into the train line.

25. An air brake apparatus comprising a train line, a brake cylinder, an auxiliary 105 reservoir, a triple valve, a train line augmenting reservoir, a valve device interposed between said augmenting reservoir and the train line said valve device operating upon a reduction of train line pressure to open a 110 valve between the train line and the augmenting reservoir to discharge augmenting reservoir air into the train line and upon an increase of train line pressure to close said valve to prevent recharging the augmenting 115 reservoir through said valve, and means for permitting the slow recharging of the augmenting reservoir from the train line after the closure of said valve.

26. An air brake apparatus comprising a 120 train line, a brake cylinder, an auxiliary reservoir, a triple valve, a train line augmenting reservoir, a valve device interposed between said augmenting reservoir and the train line, said valve device operating upon 125 a reduction of train line pressure to open a valve between the train line and the augmenting reservoir to discharge augmenting reservoir air into the train line and upon an increase of train line pressure to close said 130

- valve to prevent recharging the augmenting reservoir through said valve, means constantly tending to assist train line pressure to close said valve, and means for permitting the slow recharging of the augmenting reservoir from the train line after the closure of said valve. 45
27. An air brake apparatus comprising a train line, brake cylinder, auxiliary reservoir, triple valve, a train line augmenting reservoir, a valve device interposed between the train line and the augmenting reservoir, a movable abutment therein subject to train line pressure and augmenting reservoir pressure, a valve controlled by said abutment and adapted to be closed by train line pressure and to be opened by augmenting reservoir pressure, and a restricted recharging port connecting the augmenting reservoir with the train line. 50
- 10 28. An air brake apparatus comprising a train line, brake cylinder, auxiliary reservoir, triple valve, a train line augmenting reservoir, a valve device interposed between the train line and the augmenting reservoir, a movable abutment therein subject to train line pressure and augmenting reservoir pressure, a valve controlled by said abutment and adapted to be closed by train line pressure and to be opened by augmenting reservoir pressure, means operating on said abutment tending to assist train line pressure to close said valve, and a restricted recharging port connecting the augmenting reservoir with the train line. 55
- 15 29. An air brake apparatus comprising a train line, brake cylinder, auxiliary reservoir, triple valve, a train line augmenting reservoir, a valve device interposed between the train line and the augmenting reservoir, a movable abutment therein subject to train line pressure and augmenting reservoir pressure, a valve controlled by said abutment and adapted to be closed by train line pressure and to be opened by augmenting reservoir pressure, and a restricted recharging port connecting the augmenting reservoir with the train line. 60
- 20 30. An air brake apparatus comprising a train line, a brake cylinder, an auxiliary reservoir, a triple valve, a train line augmenting reservoir and a valve device actuated by train line pressure and augmenting reservoir pressure interposed between the said augmenting reservoir and the train line, said valve device operating upon a reduction of train line pressure to place the augmenting reservoir in communication with the train line, and upon an increase of train line pressure to place the auxiliary reservoir in communication with the train line. 65
- 25 31. An air brake apparatus comprising a train line, a brake cylinder, an auxiliary reservoir, a triple valve, an augmenting reservoir, and a valve device actuated by train line pressure, auxiliary reservoir pressure and augmenting reservoir pressure, and operating upon a decrease of train line pressure to rapidly discharge augmenting reservoir air into the train line and upon an increase of train line pressure after a service application of the brakes to discharge auxiliary reservoir air into the train line and to slowly recharge the augmenting reservoir. 70
